COMBINED BOTTLE AND CAP THEREFOR

Helen Neushaefer, New York, N. Y., assignor to Helen Neushaefer, Inc., College Point, N. Y., a corporation of New York

Application September 28, 1955, Serial No. 38,143

Term of patent 14 years

(Cl. D58—8)

Fig. 1.

Fig. 2.

Fig. 3.

Fig. 1 is an elevational view of a combined bottle and cap therefor, showing my new design;

I claim:

The ornamental design for a combined bottle and cap therefor, substantially as shown.
